Campana Sales Company, Batavia, Ill., a corporation of Delaware

Application November 13, 1946, Serial No. 134,760

Term of patent 14 years

(Cl. D80—9)

To all whom it may concern:

Be it known that I, Irving Willard Crull, a citizen of the United States, residing at Geneva, Illinois, have invented a new, original, and ornamental Design for a Combined Display Case and Lipstick Exhibit, of which the following is a specification, reference being had to the accompanying drawing, forming part thereof.

Figure 5 is an end elevational view; and

I claim:

The ornamental design for a combined display case and lipstick exhibit, substantially as shown.

IRVING WILLARD CRULL.
